(57) **CLAIM**

The ornamental design for a sock as shown and described.

DESCRIPTION

1. Sock

1.1 is a front view of our new design for a sock;

1.2 is a left side view thereof;

1.3 is a rear view thereof;

1.4 is a right side view thereof;

1.5 is a right-front perspective view thereof;

1.6 is a top-front perspective view thereof;

1.7 is a bottom view thereof; and

1.8 is a left-front perspective view thereof.

A short sock for medical use and use for sports activities; The key point of the design belongs to pattern and ornamental design; The perspective view best indicates the design.
